US0D1053750S

(12) **United States Design Patent** (10) **Patent No.:** **US D1,053,750 S**
Chen (45) **Date of Patent:** **** Dec. 10, 2024**

(54) **ORNAMENT**

(71) Applicant: **Yao Chen**, Fujian (CN)

(72) Inventor: **Yao Chen**, Fujian (CN)

(73) Assignee: **Fuzhou Aicheng Data Technology Co., Ltd**, Fujian (CN)

(**) Term: **15 Years**

(21) Appl. No.: **29/898,846**

(22) Filed: **Aug. 1, 2023**

(51) LOC (14) Cl. **11-02**

(52) U.S. Cl.

USPC **D11/158**; D11/149; D21/604

(58) **Field of Classification Search**

USPC ... D11/117, 125, 127, 130, 131, 131.1, 134, D11/135, 149, 157, 158, 184; D21/414, D21/415, 595, 604, 605, 613, 627, 654 CPC A63H 1/20; A63H 3/02; B44C 3/04; B44C 3/06; B44C 5/06; Y10S 362/806; Y10S 362/808; Y10S 493/959
